CONTAINER FOR DEODORIZING PILLS AND THE LIKE

Tancredi Strona, 6 Piazzale Dateo, Milan, Italy

Filed May 21, 1963, Ser. No. 74,998

Term of patent 7 years

(Cl. D16—2)

FIG. 1

FIG. 3

FIG. 1 is a perspective view of the container for deodorizing pills and the like showing my new design;

FIG. 2 is an exploded view of the same; and

FIG. 3 is a rear elevation thereof.

I claim:

The ornamental design for a container for deodorizing pills and the like, as shown.
